UNITED STATES PATENT OFFICE.

WILLY SCHULZ, OF FRANKFORT-ON-THE-MAIN, GERMANY, ASSIGNOR TO PROMETHEUS, FABRIK-ELEKTRISCHER KOCK- & HEIZAPPARATE, GESELLSCHAFT MIT BESCHRANKTER HAFTUNG, OF FRANKFORT-ON-THE-MAIN, GERMANY.

RESISTANCE UNIT FOR ELECTRIC HEATERS AND REGULATING RESISTANCES.

1,413,939.

Specification of Letters Patent. Patented Apr. 25, 1922.

Application filed June 17, 1916. Serial No. 104,266.

(GRANTED UNDER THE PROVISIONS OF THE ACT OF MARCH 3, 1921, 41 STAT. L., 1313.)

To all whom it may concern:

Be it known that I, WILLY SCHULZ, a subject of the German Emperor, and a resident of Frankfort-on-the-Main, Germany, have 5 invented certain new and useful Improvements in a Resistance Unit for Electric Heaters and Regulating Resistances, of which the following is a specification.

In the construction of electric heating apparatus including resistance and regulating units the means employed for supporting or securing the resistance material in position is of the greatest importance.

Such resistance units are commonly 15 formed of coils of round wire, metal tape or tubes and are only secured to a support at their ends. The effect of blows or jars to which such apparatus is necessarily subjected causes such oscillation of the coils that 20 the members thereof frequently contact, producing short circuits and shunts, especially when the coils are expanded or extended by the heat due to the passing of current therethrough. This is particularly true when 25 the units are made of thin metal such as required for obtaining a high ohmage.

With a view of overcoming this trouble, it has been proposed to wind the resistance material upon cores or bodies of insulating 30 material of various forms and in some instances provided with grooves to receive the wire or tape. However, even with such constructions the expansion of the metal is often sufficient to produce such deflection of the 35 members of the coil as to cause contact and resulting short circuiting.

If the members of the coils are separated to such an extent that undesirable contact between them is avoided the device must 40 necessarily be so large as to render it unsuitable for many uses.

Various other expedients have been tried to avoid the hereinbefore noted objections. For example, the resistance material has 45 been embedded in enamel or secured to its support by such a substance or cement. The difference in expansion of the materials results in loosening the connection between the resistance material and its support and 50 therefore such an arrangement is not satisfactory.

By the present invention, the objections incident to prior constructions are overcome

and a simple, compact, resistance unit is provided in which the danger of short circuiting due to expansion of the coils is entirely obviated.

In the accompanying drawing;

Figure 1 is an elevation of the lower end of an embodiment of the invention;

Figure 2 is a horizontal sectional view on the line II—II of Figure 1;

Figure 3 is a similar view, some of the parts being on an enlarged scale, showing the preliminary assembling of the several 65 elements.

Referring to the drawing, the resistance conductor 1 is a flat band or strip which is bent back and forth into column form, the members of each section of such conductor 70 extending between clamping devices shown as bars that extend longitudinally of the resistance column and of U-shape in cross section.

The clamping bars 2 are insulated from 75 the adjacent surface of the coil 1 by any suitable means, as for example, strips of mica 3; and between the inner faces of the coil sections are arranged strips 4 of asbestos or other insulating material.

In forming the coil the metal band 1 is wound about two yielding pins or guides 5 and after the parts 2, 3 and 4 are properly assembled the members of each section of the conductor are drawn toward each other 85 by the action of suitable screws on the clamping bars until such members are held in close contact with the compressed or compacted insulating strips 4.

The terminal coils or members of the resistance coil are provided with suitable means for connecting them with the line wires of an electric circuit. Figure 2 shows two different forms of terminal connection, namely, a tubular connector 8 and a threaded bolt 8' provided with suitable nuts. As shown, these terminal connections may be mounted on a block 7 of insulating material attached to one of the clamping bars 2.

The terminal of the coil remote from the block 7 may be electrically connected with one of the connectors 8, 8' by a conductor 9 which is positioned between the asbestos strips 4 of insulating material. If desired a plurality of such conductors 9 are employed 105 so that the coil may be divided into sections

that can be connected in series or parallel as preferred. By this arrangement a conductor of certain size and resistance may be employed for currents of different voltage.

5 For example, the two halves of a coil may be connected in parallel for a 110 volt current or in series for 220 volts.

The form of the clamping bars 2 is of considerable importance. The ribs or walls 10 of the channel bars being directed outward act to carry the heat away so that portions of the coil not directly exposed to the air may be kept suitably cool.

A resistance unit constructed in accordance with the invention may be readily immersed in an oil bath to heat it or provide an explosion-proof, oil cooled apparatus.

Having thus described the invention what is claimed is:

- 20 1. A resistance unit comprising a resistance conductor bent back and forth into column form, strips of insulating material within and extending throughout the length of said column, and means engaging both members of each section of the conductor and compressing the insulating means between them.
- 25 2. A resistance unit comprising a resist-

ance conductor bent back and forth into column form, strips of insulating material 30 within and extending longitudinally of said column, clamping bars arranged exteriorly of the column and insulated therefrom, and means connecting the clamping bars adapted to cause the members of each section of the 35 conductor to compress the intermediate strips of insulating material.

3. A resistance unit comprising a resistance conductor bent back and forth into column form, strips of asbestos extending 40 longitudinally of the column between the members of each section of the conductor, clamping bars arranged exteriorly of the column and extending parallel to said asbestos strips, means insulating the bars from 45 the conductor, and means connecting said bars and acting to cause them to compress the conductor and intermediate asbestos strips.

In testimony whereof I affix my signature 50 in presence of two witnesses.

WILLY SCHULZ.
